METHOD FOR DEBURRING COMPONENTS
OF CONSIDERABLE LENGTH

Martin M. Guibert, Port Orchard, and Curtis S. Skinner, Jr., Renton, Wash., assignors to The Boeing Company, Seattle, Wash., a corporation of Delaware

Filed Mar. 5, 1963, Ser. No. 262,894

11 Claims. (Cl. 51—7)

This invention relates to a method of deburring and surface improving, and more particularly to a method for removing burrs caused by machining, generating a small radius where the burrs were, and improving the machined surface by removing cutter marks.

In the past years many attempts to devise an economical method of deburring spar details and other long, straight components have been made by machine builders and companies associated with the airframe industry. These methods have included deburring with chemicals, deburring in a vibrating tank of abrasive media, deburring by reciprocating the workpiece in a tank of abrasive media, deburring by electro-chemical deplating, and deburring by abrasive blasting. All of the above stated prior methods proved unsatisfactory for production except the method of reciprocating a workpiece submerged in a bed of abrasive media that was fluidized by vibration. While this method was economical and produced excellent results, the maximum workpiece length was limited by the size of the abrasive bed. Since spars utilized in the airframe industry range to a length of 55 feet, the above method of reciprocating a spar of that length in a bed of abrasive media was economically prohibited due to the length of the bed required therefor.

The instant invention overcomes the objections of each of the above stated prior deburring methods by providing a method which provides the following features:

- (1) A tank of abrasive media fluidized by vibration;
- (2) A means of feeding the workpiece through the media;
- (3) A system of retaining the media while feeding through the workpiece; and
- (4) A method of reciprocating the workpiece longitudinally while it is being fed through the media.

Therefore, it is an object of this invention to provide an economical method of deburring, descaling, or surface finishing of elements of considerable length.

It is a further object of the invention to provide a method of deburring elements in a fluidized bed of abrasive media by continuous feed through and reciprocation of the elements at a predetermined rate.

Another object of the invention provides a method of deburring, by reciprocating action, a spar or other similar components, in a slurry of abrasive media while continuously feeding through the spar.

Other objects of the invention not specifically set forth above will become readily apparent from the accompanying description and drawings in which:

FIG. 1 is a diagrammatic view of an embodiment of the apparatus for carrying out the invention with certain elements being cut away or omitted for clarity;

FIG. 2 is a perspective view of one of the sealing means of the invention;

FIG. 3 shows in detail the drive mechanism of the FIG. 1 apparatus; and

FIG. 4 shows in detail an embodiment of the inertia retarder means for the feed mechanism of the FIG. 1 apparatus.

FIG. 1 shows a housing 1 having support mechanism 2, said housing being divided into three compartments, the two end compartments constituting spillage catch-tanks 3, the center compartment 4 constituting a tank for the abrasive media 5. Each of the walls of the center com-

2

partment 4 is provided with aligned sealing means 6 to permit the passage of workpiece or spar 7 therethrough, the details of sealing means 6 being described hereinafter. Each of the outer walls of compartments 3 can be provided with sealing means such as sealing means 6 of compartment 4 to provide additional sealing if desired. However, such additional sealing is not necessary. In operation abrasive media 5 completely surrounds spar 7 but has been here shown below the spar for clarity.

Powered feed rolls 8, which are in this instance Adiprene covered, are mounted on reciprocating arm mechanism 9 and feed spar 7 through housing 1, media 5 and sealing means 6 at a predetermined speed. While not shown completely, identical reciprocating arm mechanism 9 and feed rolls 8 are positioned on the left side of housing 1. Reciprocating arm mechanisms 9 are synchronized by interconnecting bar means 10 and driven via pitman 11 by drive motor and gearing mechanism 12, shown in detail in FIG. 3.

The lower feed rolls 8 are powered by motor and gearing mechanism 12 via chain or belt and pulley means generally indicated at 13. The upper feed rolls are driven by coupling means 14, for example, universal joints connected with the drive means 13. All of the feed rolls 8 are driven in synchronization. Positioned on each of arm mechanisms 9 is feed roll pressure adjustment mechanism 15.

Bucket conveyor means 16 is operatively positioned in each of spillage catch-tanks 3 (only one conveyor being shown) to return the media 5 which has spilled through sealing means 6 to the center compartment 4. The drive (not shown) for conveyor means 16 can be powered from chain and pulley means 13 or can be driven by a separate motor if desired.

As shown in FIG. 2, sealing means 6 comprises a frame 17 for holding interleaved strips generally indicated at 18 of flexible material such as rubber and sheet metal such as aluminum. Strips 18 are adjusted to the configuration of the workpiece or spar 7 and are held in place by thumb screws 19 which are screw threaded through frame 17 to press blocks 20 against the strips 18 thus permitting the workpiece to pass through with a minimum of spillage of media 5.

The drive motor and gear mechanism 12 as shown in FIG. 3 comprises an electric motor 21 driven by any available source of power, a power train generally indicated at 22 interconnects the output shaft of motor 21 with a crank 23 which drives pitman 11 for driving reciprocating arm mechanisms 9. Power train 22 includes ring gear and pinion means 24 which powers chain and pulley means 13 for driving feed rolls 8.

FIG. 4 shows inertia retarder means for reciprocating arm mechanisms 9 to cushion the shock load at the stroke reversal point, and to assist in overcoming inertia at the start of the stroke in the opposite direction. The inertia retarder means comprises a bumper plate 25 positioned under housing 1 and rigidly attached to support mechanism 2. Interconnecting bar means 10 passes through the upper portion of bumper plate 25. Positioned on bar 10 on each side of bumper plate 25 in opposed relationship are recoil and booster spring means 26, spring means 26 being adjustably located on bar 10 by means 27 whereby the position of the spring means may be adjusted in accordance with the desired length of stroke of arm mechanisms 9.

Also shown in FIG. 4 are the vibrators to fluidize the media 5 which consist of air powered vibrators 28 attached to the bottom of the media tank (center compartment) 4 and connected with an air supply source by conduit means and controls as generally indicated at 29.

Fluidization of media 5 serves the following functions:

- (1) It lessens the resistance to the spars passing through;

(2) It causes the media to move constantly, thereby presenting fresh abrasive to the workpiece on a continuous basis. This expedites metal removal and prevents the media from loading and glazing;

(3) It rotates the mass of media vertically in the tank, thereby carrying a cleaning compound and water solution from the bottom of the tank to the work area; and

(4) It aids, to a limited extent, the deburring and surface improving action of the process.

Though not shown in the instant embodiment of the apparatus, the media 5 is supported by a sheet metal plate, located approximately 6 inches above the bottom of tank 4. The void beneath the plate and a portion of the media area in the tank is filled with a water and cleaning compound solution. The solution filled area below the plate serves the dual purposes of lessening the weight to be vibrated by reducing the media load, and of dispersing the vibration (induced at two spots on the tank bottom) evenly beneath the plate. The solution in the media functions for cleaning the media during deburring.

While the instant embodiment of the apparatus utilizes air powered vibrators, mechanical vibrators are also efficient for media fluidization and can be utilized on the apparatus, if desired.

While not shown, the apparatus includes a solution filtering and recirculating system feeding into the abrasive media.

Also, two sets of feed rolls can be mounted on each of the reciprocating arms. The rolls would be mounted in pairs with the axes at 90 degrees to facilitate grasping the workpiece by the sides, or at the top and bottom. All rolls would be driven in synchronization as in the instant embodiment.

The following example is set forth to show the advantages of the invention under actual work conditions and to set forth its effective range of operation:

Media tank length: 4 foot

Workpiece length: 12 foot

Contents:

- (1) Media-bonded aluminum oxide triangles, Size No. 2.
- (2) Media weight—106 pounds/cubic foot.
- (3) Total media in tank at maximum depth—2880 cubic inches.
- (4) Total workpiece and media contact area—576 sq. inches.
- (5) Vibration—4300 cycles per minute.
- (6) Vibration amplitude—0.015 inch.
- (7) Feed roll pressure on workpiece—184 pounds.
- (8) Media pressure/square inch/inch height—0.0709 pound.

Variables:

- (1) Media height above top of workpiece—2 to 5½ inches.
- (2) Reciprocation—65 to 130 stroke cycles/minute.
- (3) Stroke length—0 to 2¾ inches.
- (4) Feed rate—6 inches to 2¾ feet/minute.

The parts in this example were machined T section aluminum spar details. This configuration, because of the thin leg, offered a minimum contact area to the feed rolls, thus reducing the gripping capability of the rolls due to the narrow area of the workpiece and thereby providing the most severe feed conditions of any spar type.

Tests were conducted under the various combinations possible with the conditions above. Parts were fed through singly, and with one part fastened end to end with another.

While the method of the invention performed satisfactory under all of the conditions tested, the best combination of variables developed was:

- (1) Reciprocation—130 stroke cycles/minute

- 5 (2) Media height above top of workpiece—5½ inches.
(3) Stroke length—2 inches.
(4) Feed rate—2¾ feet/minute.

Under the conditions set forth directly above the parts were completely deburred, and the design-required corner radii of 0.008 to 0.010 inch developed. The deburring rate of 2¾ feet/minute was approximately five times that of manual deburring which was the only prior known method of deburring parts of considerable length.

The following are features which are incorporated into the deburring apparatus for carrying out the instant invention:

- (1) Sets of synchronized feed rolls to facilitate grasping the workpiece and feeding it through the abrasive media.

- (2) A vibratory system, with variable controls for both amplitude and frequency.

- (3) A solution filtering and recirculating system for cleaning the media.

(4) A media tank with the maximum length compatible with the shortest part planned for this process. The tank contains 6 inches of media below the workpiece, and 6 inches beyond the widest part planned for processing in the machine. The interior of the tank is designed to contain no square corners or pockets capable of causing media retention and packing at the entrance and exit ends.

(5) A quick-detach means of installing and removing the door seal retainers, the door seals being flush with the interior of the media tank.

(6) The media tank floated on springs or air cushions similar to conventional vibratory tubs.

(7) The feed rate variable from 2 to 15 feet per minute.

(8) The reciprocation rate variable from 65 to 300 stroke cycles per minute.

(9) Media flow under vibration in a circular lateral pattern with no longitudinal media flow in the tank.

The instant invention has thus provided a method which has fulfilled the vast need both in the airframe industry and in other manufacturing operations dealing with long, straight line components that require deburring, descaling, or surface finishing.

Although a particular embodiment of the apparatus for carrying out the invention has been illustrated and described, it will be obvious to those skilled in the art that various changes and modifications may be made without departing from the invention, and it is intended to cover in the appended claims all such changes and modifications that come within the true spirit and scope of the invention.

What we claim is:

1. A method of deburring, descaling or surface finishing parts including the steps of: containing a predetermined quantity of abrasive media, controllably vibrating the abrasive media for providing a circular flow pattern thereof, passing a part through the abrasive media at a predetermined rate, and controllably reciprocating the part during passage through the abrasive media.

2. The method defined in claim 1 wherein the abrasive media surrounds the part by at least 5 inches.

3. The method defined in claim 1 wherein the rate at which the part is passed through the media is in the range between 6 inches to 15 feet per minute.

4. The method defined in claim 1 wherein the step of controllably vibrating the abrasive media includes independently controlling the frequency and amplitude of the vibration.

5. The method defined in claim 1 wherein the part is reciprocated in the range between 65 to 300 stroke cycles per minute with a stroke length in the range between 0.1 to 2¾ inches.

6. The method defined in claim 2 wherein the rate at which the part is passed through the media is in the range between 6 inches to 15 feet per minute.

7. The method defined in claim 6 wherein the step of controllably vibrating the abrasive media includes inde-

pendently controlling the amplitude and frequency of the vibration.

8. The method defined in claim 7 wherein the part is reciprocated in the range between 65 to 300 stroke cycles per minute with a stroke length in the range between 5 0.1 to 2 $\frac{3}{4}$ inches.

9. The method defined in claim 1 with the additional steps of filtering and recirculating solution for the abrasive media.

10. The method defined in claim 1 wherein the vibrating media has a circular lateral flow pattern.

11. A method of deburring, descaling or surface finishing parts including the steps of: containing a predetermined quantity of abrasive media, controllably vibrating the abrasive media for providing a fluidized bed thereof, 15 passing a part within and through the fluidized bed of abrasive media at a predetermined rate, and controllably, reciprocating the part during passage through the abrasive media.
